UNITED STATES PATENT OFFICE

2,027,641

SHIRT

Sidney Heymann, Brooklyn, N. Y., assignor to
Estelle Heymann, Brooklyn, N. Y.

Application July 17, 1935, Serial No. 31,786

4 Claims. (Cl. 2—106)

This invention relates to improvements in garments, more particularly men's shirts, and one of the objects of the invention is to provide a shirt which will have the appearance of shirts of this character as hitherto constructed, but manufactured with a considerable saving in material.

Another object of the invention is to provide a garment of this character which is so constructed that it will not become misplaced or rise above the waist-band of the trousers of the wearer.

Another object of the invention is to provide a man's shirt wherein the usual tail portions of the shirt are entirely omitted, thereby effecting a saving in material and making for the comfort of the wearer.

Another object of the invention is to provide a shirt of the type described which can be laundered in the usual manner.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings wherein I have illustrated a preferred form of embodiment of my invention,

Figure 1 is an elevational view of a shirt constructed in accordance with a preferred embodiment of my invention,

Figure 2 is a fragmentary view partly broken away showing the inside of a shirt constructed in accordance with this embodiment of my invention,

Figure 3 is a front elevational view of a shirt positioned on the torso of a human figure, the flaps of the shirt at the lower end being struck back better to show the construction, and,

Figure 4 is a view similar to Figure 2 showing the manner in which the casing which forms a housing for the elastic strip may be flattened out whereby the shirt may be ironed in the usual manner.

Referring now to the drawings wherein similar reference characters refer to similar parts throughout the several views of the drawings,

The reference numeral 1 denotes the body of the shirt, the present shirt being of the type that opens in front, having the usual pleats 2 or flaps 3 which are secured together by means of the usual buttons and button holes 4 and 5 respectively. In the present instance there is a but-

ton and button hole indicated at 6 and 7 located below the waist portion of the shirt.

The reference numeral 8 denotes a casing formed of a strip of material which is stitched to the inner surface of the shirt, said casing extending around the back and side portions of the shirt to terminate at each end at positions spaced from the pleats 2 or flaps 3, as indicated at 9 and 10 respectively. The casing 8 forms a housing for an elastic strip 11, which strip extends entirely through the casing and projects from said casing at either end thereof as clearly shown in Figure 2 of the drawings.

The elastic strip 11 in the present instance is stitched to the casing 8 and to the shirt by a line 15 of transverse stitching 81 intermediate its ends and that is the only part of the strip 8 that is attached to said casing. The casing 8, it will be noted, is located intermediate the lowermost button above the waist and the lowermost button 20 below the waist.

The tie strings 12 and 13, when tied, it will be noted are located inside the shirt at its front portion, so that when the button 6 is inserted within the button hole 7, the tie strings will be entirely concealed within the short skirt portion 14 of the shirt which extends downwardly below the waist portion of the shirt. The buttoning of the shirt below the elastic fastening means serves to hold that part of the shirt below the waist-band about 30 the thighs of the wearer.

By reference to Figure 4, it will be observed that during the laundering of the shirt the casing 8 may be straightened out so that the casing and the surrounding parts of the shirt may be laundered in the usual manner. When the tie strings 12 and 13 are grasped and pulled to stretch the elastic strip 11, the release of the ends of the strings will cause said elastic strip to cause the casing and that part of the shirt adjacent thereto to take its gathered or puckered form as shown in Figure 2 of the drawings.

It will accordingly be seen that I have provided a construction which not only effects a great economy in the use of material in shirt manufacture, but which makes for the comfort of the wearer. There is no bulky material about the thighs and legs of the wearer, such as inconveniences him, and the shirt is at all times held in proper position upon the wearer.

As many changes could be made in this construction without departing from the scope of the following claims, it is intended that all matter contained in the above description or shown in the accompanying drawings shall be inter-

preted as illustrative only and not in a limiting sense.

Having thus described my invention what I claim as new and desire to secure by Letters Patent is:

- 5 1. A garment of the class described having means for holding it from rising on the wearer, comprising an elastic strap carried by the shirt at the waist portion and located on the inner surface of the shirt, tie strings fastened to the ends of the elastic band for stretching the latter about the waist of the wearer, means for fastening together the flaps of the shirt, one of said means being located below the elastic band whereby the tie strings are concealed, and means securing said elastic band at its intermediate portion to the shirt, the remainder of the band being free.
- 10 2. A garment of the class described having means for holding it from rising on the waist of the wearer, comprising an elongated casing stitched to the inner surface of the shirt at the waist portion thereof, an elastic band extending through said casing and having means for fastening together the ends of the said elastic band
- 15 25

at the front of the wearer, and means for fastening together the flaps of the shirt above and below said fastening means.

3. A garment of the class described having means for preventing it from rising on the waist 5 of the wearer, comprising an open ended casing stitched to the inner surface of the shirt at its waist portion, an elastic band positioned within said casing and stitched thereto at an intermediate portion only, and a tie string fastened to 10 each end of said elastic band.

4. A garment of the class described comprising a shirt adapted to be opened in front having the usual flaps which are adapted to be connected together, said shirt having a casing stitched to 15 its inner surface adjacent the waist portion of the shirt, said shirt having a depending skirt portion below the casing, an elastic band positioned within said casing and having its middle part stitched to the casing, the ends of the band being free for relative movement within the casing, and a tie string attached to each end of the elastic band.

SIDNEY HEYMANN. 25
